UNITED STATES PATENT OFFICE

GEORGE W. NIBBE, OF CHICAGO, ILLINOIS, ASSIGNOR TO INLAND STEEL COMPANY, OF CHICAGO, ILLINOIS, A CORPORATION OF DELAWARE

TIE PLATE

Application filed August 23, 1930. Serial No. 477,228.

My invention relates to a tie plate and has for its primary object the production of a tie plate having an arrangement of ribs on the under or tie engaging side thereof, which are so arranged that the tie plate seats firmly upon the tie without cutting the surface fibres thereof, with a substantially uniform engagement with the tie under the rail supporting surface of the tie plate so that the plate will not have a tendency to shift under the rail base, and at the same time will also firmly engage the fibres of the tie so that the plate will not skew around on the tie, and any movement will be between the base of the rail and the tie plate.

Another and further object of my invention is the provision of a tie plate having tie engaging ribs formed on the under side thereof in such manner that the plate will not warp or twist during the manufacturing operations, and particularly will retain its proper shape, gauge and surface contours while undergoing the shearing operations, regardless of the area through which the shears pass.

Another and further object of my invention is the provision of a tie plate having transversely extending spaced ribs thereon on the tie engaging side thereof, which are positioned under and extend parallel with the edges of the rail base, with other ribs formed on the plate which extend across the space on the under side of the plate between the transverse ribs and merge into said ribs at the sides thereof, whereby the plate is materially strengthened throughout the areas adjacent the transverse ribs on the inside thereof.

Another and further object of my invention is the provision of a tie plate having a plurality of triangular shaped recesses formed in the body thereof between the transverse ribs with their apexes extending in opposite directions towards the transverse ribs so that when the plate is embedded in the surface of the tie, movement of the plate in an endwise direction on the tie is resisted, and the plate is thereby secured to the tie in a better manner than what has been possible with tie plates heretofore.

It will be understood that in the manufacture of the tie plates the plates are rolled in continuous strips, preferably in the direction of the rail engaging flange, and thereafter this long plate is sheared into lengths to form tie plates. It has been extremely difficult to retain the proper thickness and surface contours of the plates during both the rolling and the shearing operations because the plate does not cool uniformly, due to its unequal thickness at various points, and also during the shearing operations the cutting shear may bend or warp the plate, because in the arrangement of the ribs the plate does not possess uniform strain resisting qualities throughout the entire area of the section.

In my improved form of tie plate the arrangement of the ribs is such that regardless of where the shear may pass through the plate, the plate tends to remain true to gauge, and will not easily be thrown out of proper plane by the shearing operation.

Another and further object of my invention is the provision of a tie plate which is light in weight and yet possesses a maximum amount of strength due to the distribution of the metal in the plate and the arrangement of the ribs whereby the areas of the plate which are subject to the greatest stresses are strengthened, with recesses formed in the body of the plate into which the tie extends when the plate is in service, so the plate is firmly seated on the tie.

Another and further object of my invention is the provision of a tie plate having ribs thereon which extend parallel with the edges of the rail base and have their maximum thickness directly under the edges of the rail base where the strain is greatest, with the formation of connecting ribs preferably diagonally extending across the under surface of the plate between these two ribs, whereby the plate is braced in a longitudinal direction and also is materially strengthened adjacent the ribs, the connecting ribs forming recesses between these ribs which have their points extending both in inward and outward directions, thereby better enabling the tie plate to engage the fibres of the tie to prevent slippage of the plate.

These and other objects of my invention will be more fully and better understood by reference to the accompanying sheet of drawings, in which—

5. Figure 1 is an end elevational view of my improved tie plate; and

Figure 2 is a bottom plan view of the tie plate illustrated in Figure 1.

Referring now specifically to the drawings 10 and in which like reference characters refer to like parts throughout, a tie plate 10 is shown having the usual transversely extending rail abutting flange 11 thereon and having the usual spike openings 12, 12 there- 15 through, through which the spikes pass in securing the plate to the tie, the spikes having the usual heads thereon which engage the upper side of the rail base.

On the under surface of the tie plate and 20 extending transversely thereof and parallel with the rail in spaced relation with each other, is a pair of ribs 13 and 14, the said ribs being adapted, on account of their rounded contour, to embed themselves into the tie with- 25 out cutting the fibres thereof, with their deepest portions substantially parallel with the outside edges of the rail base. Intermediate the transverse ribs 13 and 14 and extending parallel therewith is a narrow rib 15 of 30 less height than the ribs 13 and 14, and which serves to strengthen the plate in the area between the transverse ribs 13 and underneath the web of the rail which the tie plate supports.

35 Extending diagonally across the space in the bottom of the tie plate between the ribs 13 and 15, is a plurality of diagonally extending ribs 16, 16 which are merged together at their outer ends and into the side of the 40 transversely extending rib 13, thereby strengthening the plate in the area adjacent the rib 13 on the inner side thereof and forming a plurality of triangular shaped recessed areas 17, 17, the bases of these triangular recessed areas being adjacent the rib 15, while their apexes extend outward towards the rib 15. A plurality of other recessed areas 18, 18 are also formed by the ribs 16 which have their bases extending parallel with the rib 13, with 45 their apexes extending inwardly towards the rib 15 and terminating adjacent thereto. On the opposite side of the rib 15 in the space between the said rib 15 and the rib 14, is a plurality of other diagonally extending ribs 50 19, 19 arranged in the same manner as the ribs 16, 16 at the opposite side of rib 15, and which form triangular shaped recessed areas 20 and 21 respectively which have their bases against the rib 15 and the rib 14 respectively, 55 with their apexes extending in opposite directions so that the plate adjacent the rib 14 is strengthened both against bending and also against a twisting movement.

When the tie plate is placed upon a tie 60 65 and into engagement with the surface there-

of, movement of the plate is resisted because of the engagement of the ribs 16 and 19 respectively in the fibres of the tie, in addition to the resistance afforded by the ribs 13, 14 and 15. Because the tie plate is firmly held in engagement with the tie, the channels formed in the tie by the ribs 13 and 14 will not become enlarged, as is common with tie plates of the present construction. This movement will also be resisted by the diagonally extending ribs 16 and 19 because these ribs will have embedded themselves in the tie, and the triangular shaped portions of the tie which fit into the recesses 17, 18, 20 and 21 will serve to hold the tie plate in proper relation with the tie to prevent a turning movement and also to prevent slippage of the tie plate upon the surface of the tie. The triangular shaped recesses receive similarly shaped portions of the tie when the tie plate is placed in service upon a railway tie for the purpose of preventing the skewing around of the tie plate under the rail.

It will be understood that the surfaces of the recessed areas extend slightly into the body of the plate, and that these recesses are not formed merely by the diagonally extending ribs. In the manufacture of the plate the ribs 15, 16 and 19 are formed of the metal lying in the area between the ribs 13 and 14, so that in effect a portion of this metal is removed to form the ribs 16 and 19 respectively, resulting in the production of a tie plate having strengthening ribs extending diagonally across the area between the tie engaging ribs 13 and 14, with the recesses being formed in the body of the plate, so that the entire area under the rail base is stiffened or braced by these ribs, with recesses being formed in the bottom of the plate in such manner that it engages the tie without slipping or without mutilation of the fibres of the tie and the destruction of the tie itself, so that long life is accorded the tie and maximum support provided for the rail with a minimum of weight in the tie plate. I may find it expedient to omit the rib 15 in the manufacture of the tie plate, and the direction and arrangement of the strengthening ribs may be also slightly altered, if desired.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A tie plate having a rail bearing upper surface with a rail abutting flange thereon, a pair of tie engaging ribs extending transversely on said plate on the under side thereof, an intermediate rib extending parallel

with said first mentioned ribs, and a plurality of diagonally extending ribs merging into said central rib and said transversely extending ribs whereby a plurality of triangular shaped recesses are formed on the under side of said tie plate.

2. A tie plate having a rail bearing upper surface with a rail abutting flange thereon, a pair of transversely extending ribs on said plate on the under side thereof, an intermediate rib extending parallel with said transversely extending ribs, and a plurality of diagonally extending ribs merging into said central rib and said transversely extending ribs whereby a plurality of recesses are formed on the under side of said tie plate, the said recesses being triangular in shape and having their apexes extending in opposite directions.

20 3. A tie plate having a rail bearing surface on the upper side thereof, with a rail abutting flange thereon, transversely extending ribs on the under side thereof having their thickest portions underneath the edge of the rail base, a plurality of diagonally extending ribs on the under side of said tie plate, each pair of which merge into each other and into said first mentioned ribs at their outer points thereof and cross each other at a point central of said tie plate whereby a plurality of triangular shaped spaces are formed in the bottom of said tie plate having their apexes extending in opposite directions.

4. A tie plate having a rail bearing upper surface with a rail abutting flange thereon, a pair of spaced transversely extending ribs on the under surface thereof, and a plurality of other angularly extending ribs spanning the space between said transversely extending ribs and merging into said transversely extending ribs the said ribs spanning the space between the transversely extending ribs being in a different plane than said transversely extending ribs and merging into said transversely extending ribs at their ends.

5. A tie plate having a rail bearing upper surface with a rail abutting flange thereon, a pair of spaced transversely extending ribs on the under surface thereof, and a plurality of other ribs extending angularly in two directions and spanning the space between said transversely extending ribs, the ends of said last mentioned ribs extending into and merging with said transversely extending ribs, the said transversely extending ribs and said spanning ribs being in different planes and merging into said transversely extending ribs at their ends.

6. A tie plate having a rail bearing upper surface with a rail abutting flange thereon, a pair of spaced transversely extending ribs on the under surface thereof, and a plurality of other ribs spanning the space between said transversely extending ribs and merging into said transversely extending ribs, the said ribs

extending in diagonal directions across the space between said transverse ribs, the said transversely extending ribs and said spanning ribs being in different planes and merging into said transversely extending ribs at 70 their ends.

7. A tie plate having a rail bearing upper surface with a rail abutting flange thereon, a pair of spaced transversely extending ribs on the under surface thereof, and a plurality of other ribs spanning the space between said transversely extending ribs and merging into said transversely extending ribs, the said ribs extending in diagonal directions across the space between said transverse ribs, with recesses being formed in the body of said plate between said transversely extending ribs, the said transversely extending ribs and the spanning ribs being located in different planes on said tie plate and merging into said transversely extending ribs at their ends.

8. A tie plate having a rail bearing upper surface with a rail abutting flange thereon, a pair of spaced transversely extending ribs on the under surface thereof, and a plurality of other ribs spanning the space between said transversely extending ribs and merging into said transversely extending ribs, the said ribs extending in diagonal directions across the space between said transverse ribs, with recesses being formed in the body of said plate between said transversely extending ribs, the said recesses being triangular in shape and having their apexes extending in opposite directions, the said transversely extending ribs and the spanning ribs being located in different planes on said tie plate and merging into said transversely extending ribs at their ends.

9. A tie plate having a rail bearing surface on the upper side thereof with a rail abutting flange thereon, transversely extending ribs on the under side thereof having their thickest portions under the edge of the rail base, and a plurality of diagonally extending ribs on the under side of said plate, the said diagonally extending ribs and the transversely extending ribs being in different planes with the diagonally extending ribs merging into the transversely extending ribs at their sides.

10. A tie plate having a rail bearing surface on the upper side thereof with a rail abutting flange thereon, transversely extending ribs on the under side thereof having their thickest portions under the edge of the rail base, and a plurality of diagonally extending ribs on the under side of said plate merging into the base of the transversely extending ribs, the said diagonally extending ribs and the transversely extending ribs being in different planes, the said diagonal ribs merging into the transversely extending ribs.

11. A tie plate having a rail bearing surface on the upper side thereof with a rail abutting flange thereon, transversely extend-

- ing ribs on the under side thereof having their thickest portions under the edge of the rail base, and a plurality of diagonally extending ribs on the under side of said plate merging into each other at their outer ends and into the base of the transversely extending ribs, the said diagonally extending ribs and the transversely extending ribs being in different planes, the said diagonal ribs extending into the transversely extending ribs at their sides.
- 10 12. A tie plate having a rail bearing surface on the upper side thereof with a rail abutting flange thereon, transversely extending ribs on the under side thereof having their thickest portions under the edge of the rail base, and a plurality of diagonally extending ribs on the under side of said plate merging into each other at their outer ends and into the base of the transversely extending ribs,
- 15 20 the said diagonally extending ribs and the transversely extending ribs being in different planes, each adjacent pair of diagonally extending ribs crossing each other at their centers thereof and converging with another rib
- 25 at each of its outer ends and into said transversely extending ribs.

Signed at Chicago, Illinois, this 20th day of August, 1930.

GEORGE W. NIBBE.
